United States Patent Office

Des. 204,240
Patented Apr. 5, 1966

204,240

DRIVE-IN-RESTAURANT BUILDING

Harvey R. Kaufman, 1310 Echo Park Ave.,
Los Angeles, Calif.

Filed May 13, 1965, Ser. No. 85,252

Term of patent 14 years

(Cl. D13—1)

Fig. 1.

Fig. 2.

FIG. 3.

FIG. 4.

FIGURE 1 is a perspective view of the architectural character of the said building.

FIGURE 2 is a front elevational view of the said building.

FIGURE 3 is a side view of the said building showing the design of the side opposite the one shown in FIGURE 1 hereof.

FIGURE 4 is a back elevational view of the said building.

The dominant features of my design reside in the portions shown in full lines.

I claim:

The ornamental design for a drive-in-restaurant building, as shown and described.
